ABSTRACT OF THE DISCLOSURE

A process for preparing nitroalkanes by reacting a primary or secondary alkyl nitrate and an alkali metal nitrite in the presence of an inert solvent.

SUMMARY OF THE INVENTION

This invention relates to a process for the preparation of nitroalkanes. In a particular aspect, this invention relates to a process for the preparation of nitroalkanes by reaction of a primary or secondary alkyl nitrate and an alkali metal nitrite in the presence of an inert solvent. In a further aspect, this invention relates to a process for the preparation of nitroalkanes by reaction of a primary or secondary alkyl nitrate and an alkali metal nitrite in the presence of an inert solvent and a nitrite ester scavenger.

Nitroalkanes are commonly prepared by the nitration of an aliphatic hydrocarbon with nitric acid in either the liquid or the vapor phase. The nitric acid nitration procedure results in the production of a mixture of nitroalkanes. Also, this procedure is generally not suitable for the production of the "higher" nitroalkanes; that is to say, nitroalkanes having more than about 4 carbon atoms.

Nitroalkanes have also been prepared by the reaction of an alkyl halide and sodium nitrite. This procedure is based on studies conducted by Kornblum et al. and is discussed in detail in Journal of the American Chemical Society, 78, 1497—1501 (1956) and in Journal of Organic Chemistry, 22, 455 (1957). The reported procedure results in the preparation of a single nitroalkane and may be used to obtain higher nitroalkanes. Despite these significant advantages, it has not proven generally suitable, principally because of the difficulty in obtaining the alkyl halide starting material, especially the secondary alkyl halide, in relatively pure form.

It is an object of the present invention to provide a process for the preparation of nitroalkanes.

It is a further object of the present invention to provide a process for the preparation of nitroalkanes by which a single nitroalkane is obtained.

It is a still further object of the present invention to provide a process for the preparation of higher nitroalkanes.

It is an additional object of the present invention to provide a process for the preparation of nitroalkanes from alkyl nitrates.

Other objects and advantages of the present invention will be apparent from the specification and appended claims.

It has been discovered in accordance with the present invention that nitroalkanes are obtained by reacting an alkyl nitrate with an alkali metal nitrite in the presence of an inert solvent. The reaction is suitably employed for the production of higher nitroalkanes and results in the production of a single nitroalkane.

DETAILED DESCRIPTION

In carrying out the process of the present invention,

the alkyl nitrate and alkali metal nitrite are reacted under reaction conditions in the presence of an inert solvent.

The process is conducted at a temperature sufficient to obtain the nitroalkane but insufficient to cause substantial decomposition of the nitroalkane. Temperatures below about 30° C. are generally not practical due to the slow rate of reaction, while temperatures above 120° C. tend to cause substantial decomposition of the nitroalkane. A temperature in the range of from about 45 to about 70° C. is generally preferred.

The molar ratio of alkali metal nitrite to alkyl nitrate may be varied over a wide range, with a ratio of alkali metal nitrite to alkyl nitrate in the range of from about 2.0:1.0 to about 1.0:1.0 being typically employed. A molar ratio of alkali metal nitrite to alkyl nitrate of approximately 1.5:1.0 to about 1.1:1.0 is preferred.

The process of the present invention is conducted in the presence of an inert solvent for the alkali metal nitrite and the alkyl nitrate. The amount of solvent employed should, of course, be sufficient to dissolve both the alkali metal nitrite and the alkyl nitrate. Any suitable solvent which is inert to the reactants and the reaction products may be employed. Examples of suitable solvents include hexamethylphosphoramide (HMPA), dimethyl sulfoxide (DMSO), dimethyl formamide (DMF), monomethyl formamide, and the like. Because of ready availability and the excellent results obtained therewith, DMSO and HMPA are preferred.

As previously indicated, the alkyl nitrate should be a primary or secondary alkyl nitrate, with primary alkyl nitrates being preferred. Alkyl nitrates containing from 1 up to about 20 carbon atoms are typically employed. Examples of such alkyl nitrates include butyl nitrate, propyl nitrate, octyl nitrate, ethylene glycol mononitrate, 2-octyl nitrate, decyl nitrate, 2-heptyl nitrate, 1,5-pentamethylene glycol dinitrate, phenylethyl nitrate, dodecyl nitrate, isopropyl nitrate, pentadecyl nitrate, 2-chloroethyl nitrate and the like.

Any suitable alkali metal nitrite may be employed in the process of the present invention. Examples of such suitable nitrates include sodium nitrite, potassium nitrite, and lithium nitrite. Because of its ready availability and the excellent results obtained therewith, sodium nitrite is preferred.

In order to prevent unwanted destruction of the nitroalkane by nitrite esters which are also formed during the reaction, it is preferred to employ a scavenger for these nitrite esters. The amount of nitrite ester scavenger used in the process will vary and will depend principally on the particular alkali metal nitrite, the particular alkyl nitrate, the solvent and the temperature employed. A molar ratio of nitrite ester scavenger to alkali metal nitrite in the range of from about 2.0:1.0 to about 0.1:1.0 is typically employed with a molar ratio of from about 1.0:1.0 to about 0.5:1.0 being preferred. Any suitable nitrite scavenger may be employed. Examples of such suitable scavengers include the malonate esters such as ethyl malonate, phloroglucinol, catechol, resorcinol, and the like, with ethyl malonate being preferred. These scavengers are converted to their nitroso derivatives by reaction with the nitrite esters. The nitroso derivatives do not destroy the nitroalkanes.

The nitroalkanes prepared in accordance with the present invention may be recovered by any suitable procedure. For example, the recovery may be accomplished by distillation or by extraction with a suitable solvent, such as ethyl ether or petroleum ether followed by drying or distillation.

The invention will be understood more fully by reference to the following specific examples. It is understood that the examples are presented for the purpose of illus-

tration only and are not intended as a limitation of the invention.

Example 1

To a three neck reaction vessel equipped with thermometer, stirrer, condenser and heating mantle were charged 60 ml. of DMSO. To the DMSO were added 5.26 grams (0.05 mole) of propyl nitrate, 5.52 grams (0.08 mole) of sodium nitrite and 6.41 grams (0.04 mole) of ethyl malonate with stirring to form a solution. The resulting solution was then stirred for a period of two hours during which period the temperature of the solution was maintained at approximately 65° C. Upon completion of the reaction period, the resulting reaction mixture containing 1-nitropropane was poured into a vessel containing water and then extracted with ethyl ether. The resulting mixture comprised an upper layer of ethyl ether and a lower layer of water. The layers were separated and the aqueous layer was twice extracted with ethyl ether. The ethereal layer and the ethereal extracts were combined, dried over anhydrous magnesium sulfate and distilled. 1-nitropropane was obtained in a conversion of 40% based on the alkyl nitrate.

Examples 2-9

Additional examples of the preparation of nitroalkanes are given in the following table. The general procedure utilized in Example 1 was employed.

TABLE 1

Example number	Product	Alkyl nitrate	Alkali metal nitrite	Nitrate scavenger	Solvent	Percent conversion based on alkyl nitrate
2	1-nitrooctane	Octyl nitrate	Sodium nitrite	Ethyl malonate	DMSO	41
3	1-nitropropane	Propyl nitrate	do	Phloroglucinol	DMSO	38
4	do	do	Lithium nitrite	do	DMSO	37
5	do	do	Sodium nitrite	Ethyl malonate	DMF	23
6	2-nitrooctane	2-octyl nitrate	do	do	DMSO	11
7	1-nitropropane	Propyl nitrate	do	None	DMSO	16
8	2-chloro-1-nitroethane	2-chloroethyl nitrate	do	Ethyl malonate	DMSO	5
9(a)	1,5-dinitropentane and	1,5-pentamethylene glycol dinitrate	do	do	DMSO	16
9(b)	5-nitro-1-pentane-ol					44

Example 10

Essentially the same procedure used in Example 1 is employed except that dodecyl nitrate is substituted for propyl nitrate to make 1-nitrododecane.

Example 11

Essentially the same procedure used in Example 1 is employed except that octadecyl nitrate is substituted for propyl nitrate and hexamethylphosphoramide is substituted for the DMSO to make 1-nitrooctadecane.

Since many embodiments of this invention may be made and since many changes may be made in the embodiments described, the foregoing is to be interpreted as illustrative only and the invention is defined by the claims appended hereto.

We claim:

1. A process for the production of nitroalkanes which comprises reacting a primary or secondary alkyl nitrate with an alkali metal nitrite in the presence of an inert solvent at a temperature sufficient to obtain the said nitroalkane but insufficient to cause substantial decomposition of the nitroalkane.
2. The process of claim 1 wherein the reaction is carried out in the presence of a nitrite ester scavenger.
3. The process of claim 1 wherein the temperature is in the range of from about 30 to about 120° C.
4. The process of claim 3 wherein the temperature is in the range of from about 45 to about 70° C.
5. The process of claim 2 wherein the nitrite ester scavenger is ethyl malonate.
6. The process of claim 1 wherein the molar ratio of alkali metal nitrite to alkyl nitrate is in the range of 2.0:1 to about 1.0:1.
7. The process of claim 2 wherein the molar ratio of scavenger to alkali metal nitrite is in the range of about 2.0:1.0 to about 0.1:1.0.
8. The process of claim 7 wherein the molar ratio of scavenger to alkali metal nitrite is in the range of about 1.0:1.0 to about 0.5:1.0.
9. The process of claim 1 wherein the solvent is hexamethylphosphoramide.

10. The process of claim 1 wherein the solvent is dimethyl sulfoxide.
